UNITED STATES PATENT OFFICE.

DAVID LAMBERT, OF CLEVELAND, OHIO.

BORING AND REAMING TOOL.

Application filed November 15, 1923. Serial No. 674,896.

To all whom it may concern:

Be it known that I, DAVID LAMBERT, a citizen of the United States, residing at Cleveland, in the county of Cuyahoga and State of Ohio, have invented certain new and useful Improvements in Boring and Reaming Tools, of which the following is a specification.

My invention relates to improvements in boring and reaming tools, and more particularly to that class or type having what are commonly known as "expanding cutters."

The invention further relates to an improved cutter carrying head particularly designed and adapted for use on a suitable line shaft or spindle of such machine tools as horizontal boring mills, lathes, and the like.

The primary object is to provide a generally improved tool of the type indicated, which will be exceedingly simple in construction, cheap of manufacture, and efficient in use.

A further and important object is the provision of an improved rotatably mounted cutter carrying head, together with improved means for simultaneously moving the blades or cutters outwardly and inwardly with the relative circumferential movements of the cutter carrying head on the driving shaft or bar.

A further and important object is the provision of an improved cutter carrying head circumferentially adjustable on the driving shaft, together with a relatively fixed head carrying suitable roughing tools adapted to initially enter the cylinder or article to be bored, such roughing tools being radially adjustable in accordance with the work desired.

A still further and very important object is the provision of an improved internally arranged locking device between the cutter carrying head and the driving shaft adapted to automatically lock said head as against retrograde movement when moved forwardly for projecting and adjusting the cutters to the desired diameter, together with improved means operable from the exterior of the cutter carrying head for releasing the locking device when rotating the cutter carrying head in a reverse direction or in cutter retracting position.

With the above mentioned and other ends in view, the invention consists in the novel construction, arrangement and combination

of parts, hereinafter described, illustrated in one of its embodiments in the accompanying drawings, and particularly pointed out in the appended claims.

Referring to the drawings, forming a part of this specification, Figure 1 is a fragmentary side elevation of the adjacent or connected working parts of a machine tool of the horizontal boring mill type equipped with a reamer or boring tool constructed in accordance with this invention.

Fig. 2, a longitudinal sectional view of the improved cutter carrying head with the cutters in a partially expanded position and the parts locked upon the shaft.

Fig. 3, a cross sectional view, taken on line 3-3 of Fig. 1.

Fig. 4, an end elevation, taken on line 4-4 of Fig. 1.

Fig. 5, a perspective view of one of the radially movable blades or cutters detached from the cutter carrying head.

Fig. 6, an end view of the same.

Fig. 7, a view of the inner or spiral face of one of the relatively fixed heads, detached.

Fig. 8, a similar view of the opposite relatively fixed head, detached.

Similar numerals of reference designate like parts throughout all the figures of the drawings.

The improved tool is adapted to be used either as a reamer or as a boring tool, the present embodiment of the invention being particularly well adapted for use in boring large heavy articles, such as engine cylinders, or the like.

In the present instance I have shown the improved tool in connection with a machine tool of the horizontal boring mill type having the usual vertically adjustable bearing head or block 1, carrying one end of the boring bar 2, the latter communicating with and being driven by the usual mechanism.

The work to be operated upon, such for example, as the cylinder 3, is suitably secured to the table 4, the latter with the connected feeding mechanism being adjusted and fed in the usual manner.

In the present instance I have shown my cutting mechanism arranged and adjusted for use as a boring tool. The improved mechanism comprises a cutter carrying head 5, circumferentially movable on the bar 2 when it is desired to adjust the cutter carrying blades, said head 5 being adapted

to be locked on such bar in its varying circumferential positions, as hereinafter referred to.

As a means of simultaneously expanding or retracting the blades or cutters 6, the latter are mounted in radially extending cutter blade receiving and carrying recesses or guide-ways 5^a of the head 5, a pair of relatively fixed heads 7 and 8 in the specific form of disks are mounted on the shaft 2, said fixed heads or disks being provided on their inner sides with spirally arranged ribs 7^a and 8^a, respectively, (see Figs. 7 and 8) forming spiral grooves to receive and carry the teeth or projections 6^a on the ends of the blades or cutters 6. As a means of connecting the heads 7 and 8 upon the shaft 2 to prevent relative circumferential movement, the shaft 2 and the shaft receiving openings of the heads 7 and 8 are provided with suitable key-ways to receive and contain suitable keys 9.

As a means of providing a suitable roughing tool head for carrying suitable roughing tools 10, the head 8 is provided with suitable openings 8^b to receive and contain the roughing tools, said tools 10 being adapted to be secured in any desired adjusted position by means of the set screws 11, mounted in the threaded openings 8^b, intersecting the tool carrying openings 8^a. The tools 10 are adapted to perform the initial cutting in the cylinder opening of the article to be reamed or bored out, such for example, as the cylinder 3 as the latter is advanced longitudinally and axially over the cutter carrying mechanism.

As a means of adjusting the head 7 toward and from the head 8 for the insertion or removal of cutters 6 in the head 5, and also for permitting the relative rotation of the latter when unlocked on the shaft 2 in the operation of projecting or retracting the cutters to any desired adjustment, the head 7 is longitudinally adjustable on its key, said adjusting and clamping mechanism, in the present instance, comprising a collar 12, threaded on its interior and mounted on a threaded portion 2^a of the shaft 2. As a means also of taking up the end thrust incident to such clamping action of the head 7 toward the head 8, the shaft 2 is provided with a shoulder 2^b to engage with the head 8, as shown most clearly in Fig. 2 of the drawings. The collar 12 may be provided on its outer periphery with wrench pin openings 12^a, to receive the pins or projections of a wrench of this type.

As a means of automatically locking the cutter carrying head 5 as against retrograde movement and when such cutter carrying head is moved forwardly for projecting the cutters 6 to the desired adjustment, and also as a means for releasing the locking mechanism for returning said head 5 in a re-

verse direction for retracting the cutters in the adjusting operation, I provide an improved internally arranged locking device between said cutter carrying head 5 and the shaft 2. In the present instance, such locking mechanism comprises a locking roller or pawl 13, arranged in a recess 5^b of the head 5, said recess 5^b communicating with the shaft 2 and being provided on its outer portion with an inclined or wedge shaped surface 5^c, extending tangentially of the shaft 2 so that as the shaft 2 is rotated from left to right the relative movement between the shaft and the cutter carrying head will cause the pawl roller 13 to wedge into locking or holding engagement between the surfaces of the shaft 2 and the part 5^c. As a means of normally holding the pawl roller 13 into locking relation with the surface 5^c and the shaft, a bow spring 14 may be interposed between the base portion of the recess 5^b and the roller, the outer ends of the bow spring 14 engaging with the outer ends of the roller, as shown most clearly in Figs. 2 and 3 of the drawings.

By reason of the relative arrangement and construction of the parts it will be seen that when the driving shaft 2 is being driven, and the head 5 and its cutters 6 are in locked position for work, that should there be any slippage between the parts 5 and 2 by the circumferential thrusts received by the cutters in the work, such relative movement will merely retract the cutters slightly and thus not enlarge or dig into the opening being formed in the article. It will be seen also that the lock only acts to prevent retrograde movement of the cutter carrying head 5 and that the latter may at any time be moved forwardly in a cutter expanding position by simply loosening somewhat the heads 7 and 8 which engage with the toothed ends of the cutters.

As a means of moving the locking pawl roller 13 for releasing the lock and holding the same in such unlocked position upon and during the retrograde or cutter retracting rotation of the head 5 and for so releasing by means operable from the exterior of such head, the median portion of the pawl roller recess 15^b is intersected by a threaded opening 5^d extending to the surface of the head, said threaded portion 5^d being provided with an adjusting screw 5^e. The conical portion 5^b of the screw 5^e intersects the wedge shaped surface 5^c of the opening or recess and engages with the adjacent portion of the roller so that as the screw 5^e is moved forwardly in the opening by a wrench or tool the roller 13 will be moved out of operative relation to the inclined surface 5^c and against the resistance of the follower bow spring 14. When the pawl 13 is held in such unlocked position the cutter

carrying head 5 may be moved freely forwardly or rearwardly on the shaft 2 for the desired expanding or retracting movements of the cutters 6 until the desired adjustment 5 or diameter is secured. Upon the release of such pawl roller 13 by the unscrewing or retraction of the screw 5^a such pawl roller will automatically lock the head 5 as against retrograde movement on the shaft 2 as the latter is driven and will permit the forward or blade projecting movement on the shaft at any time and will automatically lock such head and cutters as against retrograde movement at any position so attained, as 15 above explained.

Having thus described one of the embodiments of my invention, without having attempted to set forth all the forms in which it may be made, or all the modes of its use, 20 what I claim and desire to secure by Letters Patent is,—

1. In a line reamer, a line shaft carrying spaced circumferential heads having spirals, a cutter carrying head provided with radially movable cutters having teeth engaged by said spirals, an internally arranged locking device between said cutter carrying head and shaft adapted to automatically lock said head against relative rearward movement when moved forwardly for projecting the cutters into operative set positions, and means operable from the exterior of said head for releasing said locking device for 25 rotating said head in an opposite direction 30 in cutter retracting relation.

2. In a cutter for machine tools, a tool carrying bar, relatively fixed heads thereon provided with spirals, a relatively circumferentially movable cutter carrying head on 40 said bar between said fixed heads, radially movable cutters carried by and projecting from said head in engagement with said spirals, means for locking said head on said bar between said fixed heads, and means for

moving and holding said locking mechanism 45 in released position for turning said head forwardly or rearwardly relatively of said bar for projecting and retracting said cutters, respectively.

3. In a line boring or reaming device for 50 machine tools, a line shaft provided with circumferentially fixed heads having right and left handed spiral grooves on their inner sides, a head provided with radially movable cutters having teeth engaged by said 55 spiral grooves, means for moving one of said relatively fixed head longitudinally toward and from said cutter carrying head when adjusting the latter, means for automatically locking said cutter carrying head in 60 variable circumferential positions as against retrograde movement, and means operable from the exterior of said cutter carrying head for releasing said locking means and permitting the reverse movement of said 65 head to retract the said cutters.

4. In a line cutter for machine tools, a line shaft provided with relatively circumferentially fixed heads having right and left handed spiral grooves on their inner sides, 70 a circumferentially movable cutter carrying head provided with movable transverse cutters having teeth projected into engagement with said spiral grooves, means for moving one of said circumferentially fixed heads longitudinally toward and from the opposite head and toward and from said cutter carrying head when adjusting the latter, means for locking said head in varying circumferential positions as against 75 movement in one direction, and automatic means for releasing said locking means for permitting opposite circumferential movement of said head to project or retract the 80 said cutters.

In testimony whereof I have affixed my signature.

DAVID LAMBERT.
